CHARLES T. WESTLAKE, OF ST. LOUIS, MISSOURI, ASSIGNOR TO TRANSOM DRAFT GEAR COMPANY, OF ST. LOUIS, MISSOURI, A CORPORATION OF DELAWARE.

TRANSOM DRAFT-GEAR.

1,196,998.

Specification of Letters Patent.

Patented Sept. 5, 1916.

Application filed March 1, 1915. Serial No. 11,360.

To all whom it may concern:

Be it known that I, CHARLES T. WESTLAKE, a citizen of the United States, residing at St. Louis, Missouri, have invented a certain new and useful Improvement in Transom Draft-Gear, of which the following is a full, clear, and exact description, such as will enable others skilled in the art to which it appertains to make and use the same, reference being had to the accompanying drawings, forming part of this specification, in which—

Figure 1 is a plan view of my improved draft gear, the same being combined with a car transom or body bolster, parts thereof being in horizontal section. Fig. 2 is a vertical section taken approximately on the line 2—2 of Fig. 1. Fig. 3 is a perspective view of a key utilized as a connecting member between the coupler shank and draw bar. Fig. 4 is a cross section taken approximately on the line 4—4 of Fig. 1. Fig. 5 is a perspective view of the yoke which is connected to the rear end of the draw bar and which carries the springs and spring casing of the draft gear. Fig. 6 is a perspective view of the spring casing forming a part of my improved draft gear, the mating parts of halves of said casing being slightly separated. Fig. 7 is a horizontal section through a transom or body bolster and showing a modified form of my improved transom draft gear.

My invention relates generally to railway car construction and more particularly to a transom draft gear of tandem type, the principal object of my invention being to generally improve upon the construction of the present types of transom draft gears, and to provide a comparatively simple construction which can be easily and quickly assembled or taken apart, and which, in service, will insure a uniform distribution of the buffing and pulling strains through the transom or bolster and the underframe with which the same is associated.

Further objects of my invention are, to construct a transom draft gear which is compact, particularly in transverse dimensions, thereby permitting it to be readily utilized in connection with underframes where the center sill members are located comparatively close together; to provide in a transom draft gear, a comparatively sim-

ple and compact arrangement of tandem springs, further to provide a spring casing which combines with the yoke in forming a combined housing and support for the springs, and further to construct either the spring casing or the yoke in sections so that said parts may be readily assembled or taken apart and which parts are held in assembled relation by the springs with which they cooperate.

With the foregoing and other objects in view, my invention consists in certain novel features of construction and arrangement of parts, hereinafter more fully described and claimed.

In the drawings I have shown the draft gear associated with a cast metal transom or bolster, the same including a top plate 10 and bottom plate 11, which latter is provided with a center bearing 12, preferably integral. Uniting the central portions of the top and bottom plates are vertically disposed transversely extending webs 13, and formed in the front portions thereof are inwardly extending notches 14. Formed integral with the top plate 10 near the longitudinal axis of the transom and between the webs 13 is a depending flange 15 and formed integral with the bottom plate is a corresponding upwardly projecting flange 16.

The draw bar extension 17 forming a part of my improved draft gear is preferably in the form of an elongated hollow member, preferably cast and substantially square in cross section. Formed in the forward end of this extension is a pocket 18 open in front and at the top, and formed integral with the front edge of the bottom wall of said pocket is a transversely disposed flange 19. Formed in the side walls of this pocket are openings 20 which serve as key seats.

The rear end of the coupler shank 21 is of such size and form as to fit snugly within the pocket 18 and the underside of said shank is provided with a shoulder 22 which bears directly against the flange 19.

A bolt 23 passes vertically through the rear end of the coupler shank and the bottom wall of the pocket and extending transversely through the rear portion of the coupler shank is a key 24, the ends of which are seated in the openings 20 and the outer faces of said ends lying flush with the outer faces of the side walls of the pocket. To secure

the key against displacement, notches 24^a are formed in both edges of the key and when said key is properly positioned for use, the bolt 23 occupies the rear one of said notches. 5 Ordinarily, the key utilized for connecting the coupler shank to the draw bar extension is formed with a projection or head on one end, the same occupying considerable space and the outer end projects some little dis- 10 tance beyond the opposite wall and is provided with a cotter or like device to prevent displacement. These projecting ends of the key occupy considerable space and prevent the requisite sidewise movement of 15 the forward portion of the draw bar extension within the available space between the center sills of the car. With my improved construction the key does not project beyond the side walls of the draw bar extension, and 20 thus the forward portion of the extension has a much greater latitude of transverse movement.

Formed in the rear portions of the side walls of the extension 17 are longitudinally disposed slots 25 and passing therethrough is a key 26, the outer end portions of which occupy and extend beyond the notches 14 of webs 13. Positioned on the outer ends of this key 26 are washers 27, the same being 30 held in place by cotters 28.

The yoke 29 forming a part of my improved draft gear is preferably formed in a single piece and comprises parallel legs 30, a rear plate or spring seat 31, and an intermediate plate 32.

The forward ends of the legs 30 are provided with suitable openings 33 which receive the key 26. When the yoke is properly connected to the extension 17, the legs 30 of 40 the yoke occupy positions immediately adjacent the inner faces of the webs 13.

The spring casing forming a part of my improved draft gear is preferably formed in mating parts constructed so as to interlock 45 with each other and when said casing is properly associated with the yoke and draw bar extension, it is held against displacement and serves as a support and housing for the springs. One of the members of the casing 50 comprises a plate 34 provided at its forward end with a depending plate 35, the same being notched as designated by 36 and the inner lower face of said plate 35 is cut away to the sides of the notch so as to form compound curved faces 37. At the opposite end of plate 34 is a depending plate 38 and an outwardly extending plate 39, which latter serves as a stop and also as a housing for the rear springs of the device.

60 Formed on the outer face of the lower portions of the depending plate 38 is an outwardly projecting spring centering lug 40 and the outer portions of the lower end of plate 38 to the sides of this lug are cut away to form compound curved faces 41.

The opposite member of the casing is substantially like the member just described and comprises a plate 34^a, end plates 35^a and 38^a, and an outwardly projecting stop and spring housing plate 39^a. The outer portions of the end of plate 35^a are cut away at the corners to form compound curved faces 37^a which are adapted to interlock with the corresponding curved faces 37 on plate 36 and the central portion of said plate 35^a between the compound curved faces is left full as designated by 42 and which part fits snugly within the notch 36 when the two parts of the casing are properly assembled. 70 75

Formed integral with the inner face of plate 35^a is a spring centering lug 43. Plate 38^a is provided with a centrally arranged notch 44 which receives the central portion of the end of plate 38 and the inner portion of plate 38^a at the sides of said notch 85 44 are cut away to form compound curved faces 41^a which, when the parts of the casing are assembled, interlock with the corresponding curved faces 41.

When the spring casing is properly assembled with the other parts of the draft gear, the plates 35 and 35^a bear against the rear end of the draw bar extension 17 and against transverse flanges 15 and 16 on the top and bottom plates of the bolster. Plates 90 95 38 and 38^a bear directly against the rear side of intermediate plate 32 of the yoke.

Interposed between plates 35 and 35^a and the front face of intermediate plate 32 are compression springs 45, the inner one of 100 which centers on lug 43 and interposed between plates 38 and 38^a and rear plate 31 of the yoke are compression springs 45^a, the inner one of which centers on lug 40.

In assembling the parts of my improved draft gear, springs 45^a and one-half of the spring casing are positioned in the yoke, after which springs 45 and the other half of the spring casing are entered into the side of the yoke. The interlocking portions of 105 the two parts of the casing are provided with the co-operating curved faces 37 and 37^a and 41 and 41^a and when said interlocking portions are brought together they perform the functions of wedges to slightly compress the draft springs during the assembling operation and after the parts have been properly assembled, the parts of the casing are held in assembled relation by the springs 110 associated therewith. After the yoke, spring casing and springs are assembled they are entered through the opening in the body bolster from the rear until the forward end of the spring casing engages lugs 15 and 16. The draw bar extension 17 is now placed in 115 position with its rear end bearing against the forward end of the spring casing and key 26 is now inserted through notches 14, slots 33 in the forward ends of the legs of the yoke, and through the slots 26 in the 120 125 130

sides of the extension, after which washers 27 and cotter pins 28 are applied. Buffing forces transmitted from draw bar to draw bar extension 17 are in turn transmitted directly to the spring casing and as the same moves rearwardly both sets of springs 45 and 45^a will be compressed for the reason that the rear ends of said springs bear against plates 31 and 32 of the yoke and the latter is held against rearward movement by the key 26. This key bears directly against the webs 13 of the transom, and thus the stresses are transmitted directly to said transom and to the underframe with which the latter is associated.

The slots 25 in the draw bar extension are substantially longer than the width of key 26 so as to permit free rearward movement of the extension when the same is subjected to buffing action and the clearance between the front edge of the key and the front ends of slots 25 is the same as the clearance between projections 39 and 39^a and the adjacent edges of plate 29 of the yoke so that under buffing action, the projections 39 and 39^a contact with the adjacent portions of plate 29 at the same time the front ends of slots 25 come in contact with front edge of key 26 and thus the rear portion of the extension cooperates with the projections 39 and 39^a to limit the rearward movement of the parts when the same are subjected to buffing action.

It will be understood that the cooperating parts which serve as stops to limit the rearward movement of the parts as just described come in contact with each other only under extreme buffing conditions and such contact takes place before the springs entirely close.

When the draw bar extension is subjected to pulling strains, the yoke is pulled forwardly by reason of its attachment to the extension by means of the key 26 and when such action takes place the plates 31 and 32 bear against the rear ends of springs 45 and 45^a, thereby compressing the same against the end plates of the spring housing and the latter is held against forward movement by its engagement with the flanges 15 and 16 on the transom. Thus the pulling strains are transmitted directly to the transom and the underframe with which the same is associated.

As heretofore stated, the forward movement of the yoke is limited by the engagement of the edges of plates 31 against the rear ends of plates 39 and 39^a, and which engagement takes place prior to the closing of the springs.

In some instances, it may be found desirable to make the yoke in two parts and the spring casing in a single part, and when such construction is carried out, the plates 31 and 32 are divided on transverse lines

and the mating edges of said divided plates are provided with interengaging curved faces which are in every way similar to the corresponding faces on the parts of the spring housing, heretofore described. (See Fig. 7.)

A transom draft gear of my improved construction is comparatively simple, can be cheaply manufactured, is very compact, particularly in transverse dimensions, can be readily assembled or taken apart, and is very effective in transmitting to the transom and underframe all pulling and buffing strains.

It will be readily understood that minor changes in the size, form and construction of the various parts of my improved draft gear can be made and substituted for those herein shown and described, without departing from the spirit of my invention, the scope of which is set forth in the appended claims.

I claim:

1. The combination with a transom having a draft gear opening, of a draw bar, a yoke connected thereto and positioned in said opening, which yoke is held against movement in one direction, a two-part spring casing cooperating with the yoke, springs interposed between the casing and parts of the yoke, which springs maintain the parts of the spring casing in assembled relation, and which spring casing is held against movement in one direction.

2. The combination with a transom having a draft gear opening, of a draw bar, a yoke connected thereto and positioned in said opening, which yoke is held against movement in one direction, a two-part spring casing cooperating with the yoke, the parts of which casing are provided with interlocking members, springs interposed between the casing and parts of the yoke, which springs maintain the parts of the spring casing in assembled relation, and which spring casing is held against movement in one direction.

3. The combination with a transom provided with a draft gear opening, of a draft gear occupying said opening and comprising a draw bar, a yoke connected thereto and positioned in said opening, which yoke is held against movement in one direction, a two-part spring casing cooperating with the yoke and bearing against a part of the car so that it is held against movement in one direction, and springs interposed between parts of the yoke and the spring casing, which springs maintain the parts of the spring casing in assembled relation.

4. The combination with a transom provided with a draft gear opening, of a draft gear occupying said opening and comprising a draw bar, a yoke connected thereto and positioned in said opening, which yoke

- is held against movement in one direction, a two-part spring casing coöperating with the yoke and bearing against a part of the car so that it is held against movement in 5 one direction, springs interposed between parts of the yoke and the spring casing, which springs maintain the parts of the spring casing in assembled relation, and means on the spring casing for limiting the 10 movement of the yoke relative thereto.
5. The combination with a transom provided with a draft gear opening, of a draft gear occupying said opening and comprising a draw bar, a yoke, a member connecting the draw bar and yoke, which member is adapted to engage the transom to hold the yoke against movement in one direction, a sectional spring casing associated with the yoke, and springs interposed between the 15 casing and parts of the yoke, which springs maintain the sections of the spring casing in assembled relation.
6. The combination with a transom provided with a draft gear opening, of a draft gear occupying said opening and comprising a draw bar, a yoke, a member connecting the draw bar and yoke, which member is adapted to engage the transom to hold the yoke against movement in one direction, a sectional spring casing associated with the yoke, which spring casing is held against movement in one direction by the transom, and springs interposed between the casing and parts of the yoke, which springs maintain the sections of the spring casing in assembled relation.
7. The combination with a transom provided with a draft gear opening, of a draw-bar, draft gear elements including a yoke, and a spring casing occupying the opening in the transom and connected to the draw-bar, one of which elements is made in sections to facilitate the assembling of the draft gear, and springs interposed between the 45 said elements, which springs maintain the parts of the sectional element in assembled relation.
8. In a draft gear of the class described, a draw bar, a yoke connected thereto, which yoke is provided with spring seats, a sectional spring casing coöperating with said yoke, a part of which casing bears against one of the spring seats of the yoke, and springs interposed between the casing and the spring seats of said yoke, which springs maintain the parts of the spring casing in assembled relation, said spring casing being held against movement in one direction and the yoke being held against movement in 60 the opposite direction.
9. In a draft gear for railway cars, the combination with a draw bar, of a yoke connected thereto, a two-part spring casing which is brought into assembled relation to said yoke by a movement of the parts of the 65 casing toward each other and transversely with respect to said yoke, and springs interposed between parts of said spring casing and yoke which springs maintain the parts of said spring casing in assembled relation. 70
10. In a draft gear for railway cars, the combination with a draw bar, of a yoke connected thereto, a two-part spring casing which is brought into assembled relation to said yoke by a movement of the parts of the 75 casing toward each other and transversely with respect to said yoke, springs interposed between parts of said spring casing and yoke, which springs maintain the parts of the casing in assembled relation, 80 means for holding the yoke against movement in one direction, and means for holding the spring casing against movement in the other direction.
11. In a draft gear for railway cars, a 85 spring casing formed in mating sections, portions of which interlock, and springs arranged in said casing and holding the parts thereof in assembled relation.
12. In a draft gear for railway cars, a 90 spring casing formed in mating sections, portions of which interlock, springs within said casing, which springs hold the parts of said casing in assembled relation, and spring centering lugs on said sections. 95
13. In a draft gear for railway cars, the combination with a fixed member of the car underframe, of a draw bar, a yoke connected thereto, which yoke extends through an opening in the underframe member, a 100 sectional spring casing coöperating with the yoke, which springs maintain the parts of the casing in assembled relation, springs interposed between said casing and the yoke, means for holding the yoke against movement in one direction, means for holding the casing against movement in the other direction, and means for limiting the movement of the yoke and casing toward each other. 105
14. In a draft gear for railway cars, the combination with a draw bar, of a yoke connected thereto, a two-part spring casing which is brought into assembled relation to said yoke by a movement of the parts of the 110 casing toward each other and transversely with respect to said yoke, the parts of the spring casing being provided with interengaging parts, and springs interposed between the spring casing and yoke, which springs maintain the parts of the casing in assembled relation. 120
15. In a draft gear for railway cars, a draw-bar, a yoke connected thereto, which yoke is provided with a pair of spring seats, a spring casing coöperating with said yoke and with the draw-bar, which casing is provided with a pair of spring seats oppositely arranged with respect to the spring seats on the yoke, and springs bearing on the corre- 125
- 130

sponding pairs of spring seats, said yoke and spring casing being held in assembled relation by said springs.

16. In a draft gear for railway cars, a draw-bar, a yoke connected thereto and provided with a pair of spring seats, a spring casing coöperating with the yoke and having interlocking parts which serve as spring seats, and springs bearing upon the seats on the yoke and on the casing and holding said parts in assembled relation.

17. In a draft gear for railway cars, a spring casing formed in sections, pairs of

which coöperate to form spring seats, and said parts having interlocking portions 15 which are held in engagement with each other by the pressure of the springs on said spring seats.

In testimony whereof I hereunto affix my signature in the presence of two witnesses, 20 this 10th day of February, 1915.

CHARLES T. WESTLAKE.
